UNITED STATES PATENT OFFICE.

EDWARD POSSON, OF CHICAGO, ILLINOIS.

REFRIGERATOR-CAR.

1,322,051.

Specification of Letters Patent. Patented Nov. 18, 1919.

Application filed August 14, 1916. Serial No. 114,783.

To all whom it may concern:

Be it known that I, EDWARD POSSON, a citizen of the United States, residing at Chicago, Illinois, in the county of Cook and 5 State of Illinois, have invented certain new and useful Improvements in Refrigerator-Cars, of which the following is a specification.

This invention relates to improvements 10 in cars, such as those of the type commonly known as refrigerator cars; and its purpose is to provide a sectional bulkhead for cars and to provide a convertible car which may be used as a refrigerator car for carrying 15 fruits, vegetables, meats, or other kinds of perishable freight, and which may be converted into an ordinary freight car by displacing the elements of the refrigerating apparatus so that they do not occupy any appreciable space within the car.

In refrigerator cars of the type now generally used, a refrigerant compartment or ice box is constructed within the car at each end thereof, and means is provided for introducing ice through the hatchways, located generally in the roof of the car. Such cars are commonly used for carrying fruits, vegetables, and the like, on relatively long journeys, and on the return trips of such 30 cars they are used as ordinary freight cars for containing articles of manufacture, and the like, which are shipped from the central market places to the regions where fruits, vegetables, and the like are grown. During 35 these return trips of the cars the refrigerating apparatus is not used, and it will be apparent, therefore, that the space within the car occupied by the ice boxes or refrigerating compartments is wasted.

The principal object of my invention is to provide a sectional bulkhead for a railway car, whereby the space within the car may be divided into separate compartments. Another important object of my invention is 45 to provide a refrigerator car having a refrigerant compartment, or ice bunker, of novel construction and arrangement, which may be rearranged within the car to occupy a very limited space therein when it is desired to use the car as an ordinary freight car with the refrigerating apparatus inoperative. A further feature of the invention is the provision of a partition or bulkhead separating the ice chamber from the interior 55 of the car, which partition or bulkhead may be raised in a novel manner to occupy a posi-

tion where it does not interfere with the usual freight contained within the car. A further feature is the provision of a partition or bulkhead composed of a plurality 60 of complementary sections which may be moved vertically from their normal positions and arranged adjacent the roof of the car. A still further object is to provide a refrigerant compartment having a plurality 65 of walls, each of which may be moved from its normal position to an inoperative position, wherein it occupies a relatively small space within the car. Still another object is to provide a car comprising improved 70 means for effecting a thorough air circulation within the car. Another feature is an improved air circulating floor. A further object is to provide a car having a refrigerant compartment comprising removable 75 end and side walls and a removable floor section which may be readily displaced from operative position or replaced in such position. Other objects relate to features of construction and arrangement, as will appear more fully hereinafter.

The various objects and advantages of my invention will appear more clearly from the following specification taken in connection with the accompanying drawings, in which 85 one embodiment of the invention is illustrated.

In the drawings—

Figure 1 is a vertical longitudinal section through a railway car embodying the 90 features of my invention, showing the elements of the refrigerant compartment in normal operative positions.

Fig. 2 is a view similar to Fig. 1, showing the bulkhead, side walls, and floor section 95 of the refrigerant compartment supported in inoperative positions, illustrating the arrangement when the car is converted into an ordinary freight car.

Fig. 3 is a horizontal longitudinal section 100 through my improved car, showing the location and arrangement of the refrigerant compartment when the elements thereof are in normal position, the section being taken on the line 3—3 of Fig. 1.

Fig. 4 is a vertical section, taken on the line 4—4 of Fig. 3, showing by dotted lines the arrangement of the side walls of the refrigerant compartment when they have been swung upwardly to a position adjacent 110 the roof of the car.

Fig. 5 is a perspective view of the screen

which forms the upper section of the bulk-head or partition.

Fig. 6 is a perspective view, showing one of the intermediate sections of the bulk-head or partition.

Fig. 7 is a perspective view, showing the lower ventilating section of the partition or bulkhead.

Fig. 8 is a perspective view of a latch for holding the upper hinged section of the bulkhead in normal position.

Fig. 9 is a perspective view of the pin and hook for securing the side walls of the ice bunker in inoperative positions.

Fig. 10 is a vertical longitudinal sectional view, showing the mounting of the side walls of the refrigerant compartment, the upper portion of the bulkhead, and the means for securing the sections of the bulk-head in inoperative positions; and

Fig. 11 is a detail vertical longitudinal sectional view, showing the lower end of the refrigerant compartment and the construction and arrangement of the sections of the bulkhead and the grate or floor section of the refrigerant compartment.

In the accompanying drawings I have shown my invention in connection with a railway car embodying some of the usual features of refrigerator car construction, these features including the floor 10 carried by the sills 11. Spaced upwardly from the floor is my improved subfloor 12, which I have provided for effecting a more perfect ventilation of the car. This sub-floor is formed of a plurality of floor boards or slats 12^a which are spaced from the main floor by the members 12^b, 12^c. These members constitute a spacing floor which permits a thorough air circulation within the car. The members 12^b are parallel to each other, and extend transversely of the car at intervals, while the members 12^c, extending longitudinally of the car, are each of sufficient length to unite and support two adjacent members 12^b and are staggered in their arrangement, as shown in Fig. 3, whereby a plurality of interconnected air spaces are formed which permit the cold air to pass longitudinally of the car through the sub-floor 12, and thence upwardly between the spaced apart slats 12^a. This sub-floor is preferably built in sections, and the members 12^c, at the end of each section, are projected beyond the adjacent members 12^b, as shown at 12^d, so that the projecting parts 12^a will support the members 12^b of the adjacent section. In this way the sub-floor can be readily removed from the car when desired.

Extending upwardly from the floor at the end of the car is the end wall 13, comprising the outer wall 13^a, an intermediate wall 13^b of heat-insulating material, and an inner wall 13^c which is spaced from the intermediate wall by the frame members 13^e,

thus forming air spaces 13^f. The side walls 14 of the car are constructed in a manner similar to the end walls, each side wall comprising an outer wall section 14^a, a heat-insulating lining or wall 14^b, and an inner wall 14^c which is spaced from the insulating lining. The roof 15 is of the usual form, comprising the outer roof 15^a and the inner roof 15^b, which include between them the sheets of heat-insulating material 15^c, and which are spaced apart in the usual manner and supported by the carlines 16. At the end of the car there is provided a hatchway 17, located between the purlins 18 and extending through the roof section 15. This hatchway may be of any suitable form, and closed by the usual cover, and it leads downwardly through the roof, as above described, and serves to permit ice to be placed into a refrigerant compartment, or ice bunker, located at the end of the car. This refrigerant compartment embodies the features of the present invention, and although one such compartment is preferably provided at each end of the refrigerator car, only one such compartment is herein described, since they are both similar in construction and arrangement.

The ice chamber 20 of this refrigerator compartment is separated from the interior or refrigerating chamber 21 of the car by means of a bulkhead 22, which is composed of a plurality of complementary sections which interlock with each other and are slidable vertically to permit the removal of the bulkhead for the purpose of adding the space 20 to the interior chamber 21 of the car. Each bulkhead comprises a lower air circulating section 23, a plurality of solid or closed sections 24, and an upper air circulating section or screen 25, which is in effect a continuation of the bulkhead. A floor section or grate 26 separates the ice chamber 20 from the lower cold air chamber 27, and the end wall and side walls of the ice chamber are formed by the ventilating wall sections 28 and 29, respectively. The floor section and walls of this ice chamber, including the bulkhead, are removable, as hereinbefore indicated, and the particular construction and arrangement of the bulkhead will first be described.

The lower air circulating section 23 of the bulkhead or partition comprises a metal frame which is composed of the end frame members 23^a, which are secured to the upper and lower frame members 23^b and 23^c, respectively, the last mentioned frame members being of Z-bar construction, as clearly shown in Fig. 11, for instance, where it will be seen that the flanges of the Z-bars which are adjacent the cold air chamber 27 are directed downwardly, while the flanges which are adjacent the chamber 21 of the car are directed upwardly. This frame of

the section 23 has secured thereto a supplementary frame formed from the channel bars 23^a of relatively small size, which have their lateral flanges directed outwardly 5 from each other, and which have secured thereto the air circulating screen 23^c. The downwardly extending flange of the Z-bar 23^c is adapted to engage a groove 30, which extends transversely of the car through the 10 supplementary floor 12, and the web of the upper Z-bar 23^b extends inwardly beyond the body of the frame of the lower section to serve as a support for the edge of the floor section or grate 26, which will be more 15 fully described hereinafter. The upper and lower frame members of the section 23 of the bulkhead are spaced apart and reinforced by the vertically extending frame members 23^f, and at each lower corner of 20 the section 23 there is provided a supplementary frame 23^g of channel bar construction, whereby an aperture 23^h is formed to permit access to the interior of the cold air chamber 27 from the interior of the car, 25 and to provide convenient means for manipulating the floor section when it is desired to move the same. Each end frame member 23^a has secured thereto, and projecting therefrom, a pair of cylindrical lugs or trunnions 31. These lugs are adapted to slide in 30 guideways formed by the channel bars 33, which are seated in grooves in the side walls of the car and secured to suitable frame members 34 of the side walls.

35 Each of the solid or closed sections of the bulkhead, designated by the numerals 24, is formed of upper and lower frame members 24^a and 24^b, respectively, having vertically extending frame members 24^c secured 40 thereto and extending therebetween. Suitable boards, or the like, 24^e are secured to the vertically extending members 24^d, and the whole structure so formed is covered by a sheet of metal covering 24^f. A longitudinal flange or cleat 24^g extends along the upper edge of each section 24, except the uppermost section, and each of these flanges is adapted to seat in a groove 24^h formed in the lower edge of the adjacent section 24, 45 it being understood that each section 24 is provided with one of these grooves, except the lowermost section, which seats upon the air circulating section 23. Each section 24 has a plate 34 secured to each end thereof, 50 and each plate carries two cylindrical lugs or trunnions 31 similar to the lugs 31 carried by the air circulating section 23. All of the lugs are adapted to slide in the guideways 33, and these guideways serve to hold the 55 sections of the bulkhead in position, as illustrated, for instance, in Figs. 1 and 4, where it will be seen that these sections form a partition separating the ice chamber from the interior chamber 21 of the car. Each of 60 the sections 24 has a notch or depression 24ⁱ adjacent each of its ends, the notches extending inwardly from the outer sides and adjacent the lower edges of the wall sections to serve as hand holds for elevating the sections. Adjacent the roof of the car each of 70 the guideways 33 is inclined upwardly, as shown at 33^a, and then directed horizontally, as shown at 33^b, the portions 33^b forming supports for the sections of the bulkhead after the latter have been moved upwardly 75 and thence horizontally in the guideways. The space between the upper section 24 and the adjacent part of the car roof or ceiling is closed by the section 25 previously described, which is illustrated particularly in 80 Fig. 5, and which comprises a frame 25^a formed of channel bars of relatively small section, having secured thereto the air circulating screen 25^b. This section 25 is secured to the adjacent roof section 19 by 85 means of hinges 25^c, so that the section 25 may be swung upwardly into an inoperative position, as illustrated by dotted lines in Fig. 10, for instance. When thus swung upwardly into a position adjacent the roof section, the section 25 may be engaged adjacent its free edge by a latch member 38, which is pivotally connected to the frame member 39, and arranged to swing about its vertical axis to engage the edge of the 90 section 25.

95 After the section 25 has been moved upwardly, and secured in an inoperative position as just described, the bulkhead sections 23 and 24 may be moved vertically in the 100 guideways 33, and thence horizontally in the horizontal portion of the guideways which are located adjacent the roof of the car, until they occupy the positions illustrated, for instance, in Fig. 2. The movement of the 105 bulkhead sections in the horizontal portions of the guideways is limited by the adjustable stops 41, which are secured thereto, and these sections are retained in inoperative position in the horizontal sections 33^b by 110 means of the gravity latches 42, which are pivoted on the side walls of the car at 43 and which are provided with downwardly extending shoulders or teeth 42^a adapted to engage the adjacent edge of the last bulkhead section to be moved into the horizontal portion of the guideways. When in this position the extremity 42^b of the latches will 115 rest upon the upper surface of the adjacent bulkhead section, and when it is desired to 120 return the bulkhead sections to normal operative position the latches 42 may be raised manually to permit such movement of the bulkhead sections. Then after these sections have been returned to the position illustrated 125 in Fig. 1, the latch 38 is released and the section 25 swung downwardly, where it is secured in normal position by means of the latches 44, which are pivoted on the brackets 44^a, secured to the uppermost section 24 and 130

adapted to engage the lower edge of the section 25.

The grate or floor section 26 of the ice chamber comprises the transverse cleats or slats 26^a and spacers 26^b, secured together by the rods 26^c. The inner extremities of these cleats or slats have secured to the lower edges thereof the angle bar 26^e, which is adapted to rest upon the inwardly extending part of the upper frame member 23^b of the bulkhead section 23, as previously described. Adjacent the other edge of the floor section there is mounted a frame member 46, which extends transversely of the car and forms the upper part of the end wall of the cold air chamber 27. This end wall comprises vertically extending frame members 47 having secured thereto the horizontal cleats 48; and the frame members 46 and 47 are secured to the vertically extending frame members or spacing members 50, which serve to space the inner end wall section 13^c of the car from the ventilating wall 28 of the ice chamber. Hinges 51 serve to connect the floor section 26 to the frame member 46 above referred to, and permit this floor section to be swung upwardly from its normal position, as illustrated in Figs. 1 and 11, to an inoperative position, as illustrated, for instance, in Fig. 2, where it lies alongside of the ventilating screen 28, and in which position it is adapted to be secured by means of the latches 53, which are pivoted on the ends of the grate and adapted to swing into slots in the brackets 54 attached to the side walls of the car.

The side walls 29 of the ice chamber comprise the vertically extending frame members 29^a secured to the transversely extending frame members 29^b, and these frame members have secured thereto the screens 29^c. Hinges 60 serve to provide a pivotal connection between the upper edges of these side walls 29 and the frame of the car adjacent the roof, so that when the bulkhead sections and the floor section have been moved to inoperative positions these side walls 29, one of which is hinged at a lower level than the other, may be swung upwardly and arranged to overlap each other adjacent the center of the car, as shown, for instance in Fig. 4. One of the side walls 29 is first swung upwardly and fastened by the hook 62, attached to the roof of the car, and the other side wall then moved into its upper position, after which both end walls may be locked by passing the hook 63, which is suspended from the lowermost section 29, through an aperture in the pin 64 carried by a plate 64^a attached to the car roof and arranged to pass through alining apertures in the plate 65 secured to the frame members 29^a of the end walls 29. When the walls 29 are in their normal positions parallel to the sides of the car, they are held against move-

ment by the angles 65^a secured to the lower bulkhead section 24.

In the floor of the cold air chamber, beneath the ice chamber, there is provided a drain 66^b, which may have an outlet of the usual form comprising a duct 66, having a hinged cap 66^a which permits the water to flow out of the drain 66^b, but prevents air from entering the car.

From the foregoing description it will be apparent that I have provided an improved ice bunker, into which the ice may be placed through the hatchway 17, for instance, when it is desired to use the car as a refrigerator car. After the compartments have been charged with ice, it will be apparent that a continuous circulation of air will be maintained, since the warm air collecting at the top of the car will move through the air circulating bulkhead section 25 into the upper part of the ice chamber, and the air being cooled therein will pass through the screens 28 and 29 downwardly through the space between the screens 28 and 29 and the end wall of the car, thence through the cold air chamber 27, and finally out through the air ventilating bulkhead section 23 to the lower part of the car, or through the spaces beneath the sub-floor 12 to various parts of the car. In this way a continuous circulation is maintained, while at the same time the ice chamber is thoroughly inclosed, thereby preventing moisture from entering the interior chamber 21 of the car. When the car is operated in the manner just described, it is adapted for use in shipping fruits, vegetables, or other articles which are liable to decay or become spoiled if not maintained at a low temperature. However, since articles and goods of this kind are usually shipped from one section of the country to some other section, and goods of a similar kind are not returned, the refrigerant space of a refrigerator car is usually of no value during the return trip of the refrigerator car. It will be seen that my invention overcomes this difficulty by providing means whereby the refrigerant compartments, or ice bunkers, may be used as parts of the interior chamber of the car after the elements of the compartment walls have been moved to inoperative positions where they do not interfere with the goods which are contained within the car. The construction of the bulkhead is particularly advantageous, since it permits the convenient removal of the bulkhead from its normal position, or the return of the same to its normal position by one or two operators, it being necessary to move only one section at a time. It will further be apparent that when these bulkhead sections are in inoperative positions they are held securely and cannot be accidentally displaced so as to cause injury to persons or goods in the car.

The floor section of the ice chamber and the side walls thereof may also be conveniently manipulated by one or two persons for the purpose of converting the refrigerator car 5 into an ordinary freight car, or vice versa. It will be understood that I have referred to the ice bunkers as refrigerant compartments, as distinguished from the interior chamber 21, in which the goods are placed 10 and which is commonly called the refrigerating chamber.

Although I have shown and described a particular embodiment of the invention for purposes of illustration, it will be understood that it may be constructed in various 15 different forms without departing from the scope of the invention as defined in the appended claims.

I claim—

20 1. In a refrigerator car, a refrigerant compartment having a movable wall extending transversely of the car and comprising a plurality of separate unconnected sections movable to an inoperative position adjacent the roof of the car.

25 2. In a refrigerator car, a bulkhead extending across the car and divided horizontally to form a plurality of complementary movable sections which separate the space within the car into refrigerant and refrigerating compartments.

30 3. In a refrigerator car, a refrigerant compartment having a wall comprising a plurality of complementary unconnected sections 35 extending parallel to each other, said sections being movable transversely to their longitudinal axes, and guides engaging the ends of said sections.

40 4. In a refrigerator car, a wall extending transversely of the car and comprising a plurality of slidably mounted sections, guides attached to said wall and engaging the ends of said sections, and means adjacent the roof of said car for supporting 45 said sections in inoperative position.

50 5. In a refrigerator car, a partition extending transversely of the car to form refrigerant and refrigerating chambers, said partition comprising a plurality of complementary horizontally extending sections movable vertically, and means attached to the side walls of said car for supporting and guiding said sections.

55 6. In a refrigerator car, a partition extending transversely of the car and comprising a plurality of complementary sections for dividing the car into refrigerant and refrigerating chambers, guides in which said sections are slidably mounted, and means adjacent the extremities of the guides for supporting said sections in an 60 inoperative position.

65 7. In a refrigerator car, a partition extending transversely of the car and comprising a plurality of complementary sections

for dividing the car into refrigerant and refrigerating chambers, guides in which said sections are slidably mounted, means adjacent the extremities of the guides for supporting said sections in an inoperative 70 position, and means for retaining said sections in position on the supporting means.

8. In a railway car, a refrigerant compartment having a wall comprising a plurality of movable parallel sections, and 75 guides engaging the ends of said sections and arranged to permit the moving of said sections from normal position to a position adjacent a wall of said car.

9. In a refrigerator car, a partition extending transversely of the car and comprising a plurality of complementary movable sections for dividing the car into refrigerant and refrigerating chambers, and guides extending vertically adjacent the side walls of 80 said car for supporting said sections and permitting movement thereof upwardly, said guides being extended horizontally adjacent the roof of the car to support said sections in inoperative positions.

90 10. In a refrigerator car, a sectional partition extending transversely of the car and forming separate refrigerant and refrigerating chambers, guides at the end of said sections for supporting and permitting 95 movement thereof, and air circulating means in said sections adjacent the upper and lower parts of said partition.

100 11. In a refrigerator car, a sectional partition extending transversely of the car, 100 guides at the ends of said sections for supporting and permitting movement thereof, air circulating means provided in the lower section of said partition, and a supplementary air circulating section hinged adjacent the roof of the car and arranged to engage the uppermost section of said partition.

105 12. In a refrigerator car, a sectional partition extending transversely of the car, 110 guides at the ends of said sections for supporting and permitting movement thereof, air circulating means provided in the lower section of said partition, a supplementary air circulating section hinged adjacent the 115 roof of the car and arranged to engage the uppermost section of said partition, means for securing said supplementary hinged section in position engaging the upper section of the partition, and means for supporting said supplementary section when the latter is swung upwardly adjacent the roof of the car.

120 13. In a refrigerator car, a sectional partition extending transversely of the car, 125 guides at the ends of said sections for supporting and permitting movement thereof, air circulating means provided in the lower section of said partition, a supplementary air circulating section hinged adjacent the 130

- 5 roof of the car and arranged to engage the uppermost section of said partition, means for securing said supplementary hinged section in position engaging the upper section
 10 of the partition, means for supporting said supplementary section when the latter is swung upwardly adjacent the roof of the car, and means for supporting the sections of said partition when moved upwardly out
 15 of said guides.
14. In a refrigerator car, a sectional bulkhead extending transversely of the car, means to permit movement of the sections of said bulkhead from normal position to an
 20 inoperative position adjacent the roof of the car, supplementary side walls spaced inwardly from the side walls of the car and movable upwardly to inoperative positions, a floor section spaced upwardly from the
 25 floor of said car and movable upwardly from normal position to a position parallel to the end wall of the car, and air circulating means in said sectional bulkhead below the level of the floor section and adjacent the roof of the car. 25
15. In a refrigerator car, a partition extending transversely of the car and comprising a plurality of complementary horizontally extending sections movable to a position adjacent the roof of the car, said partition being adapted to divide the car into refrigerant and refrigerating chambers, and a movable floor section attached to a wall of the car and movable into a horizontal position in the refrigerant chamber spaced 30
 35 above the floor thereof.

In testimony whereof, I have subscribed my name.

EDWARD POSSON.
